DESIGN FOR A WELDING TRANSFORMER

John A. Kern, Chicago, Ill., assignor to Atomiko,
Inc., Chicago, Ill., a corporation of Illinois

Application January 10, 1947, Serial No. 136,055

Term of patent 7 years

(Cl. D26—5)

To all whom it may concern:

Be it known that I, John A. Kern, a citizen of the United States, a resident of Chicago, in the county of Cook, State of Illinois, have invented a new, original, and ornamental Design for a Welding Transformer, of which the following is a specification, reference being had to the accompanying drawing, forming a part thereof.

Fig. 1 is a perspective view of a welding transformer showing my new design;

Fig. 2 is a side view;

Fig. 3 is a rear view;

Fig. 4 is a top view.

The characteristic features of my design reside in the portion shown in full lines,

I claim:

The ornamental design for a welding transformer, as shown and described.

JOHN A. KERN.
